UNITED STATES PATENT OFFICE.

JACOB GROSS, OF BROOKLYN, NEW YORK.

BUTTON-SHOE AND UPPER THEREFOR.

1,254,039.

Specification of Letters Patent. Patented Jan. 22, 1918.

Application filed July 29, 1915. Serial No. 42,487.

To all whom it may concern:

Be it known that I, JACOB GROSS, a citizen of the United States, resident of borough of Brooklyn, county of Kings, city and State of New York, have invented a certain new and useful Improvement in Button-Shoes and Uppers Therefor, of which the following is a specification.

This invention relates to improvements in button shoes or boots, or other forms of foot coverings.

The objects are

First: To reduce the number of seams necessary in making the upper.

Second: To avoid waste of leather in cutting the upper.

Third: To improve the appearance of the finished article.

These and further objects will more fully appear from the following specification and accompanying drawings, considered together or separately.

In the drawings,

Figure 1 is a side view of a board suitable for making my improved upper and for carrying out my improved process;

Fig. 2 is a front view of the same;

Fig. 3 is a section on the line 3—3 of Fig. 1, looking upward;

Fig. 4 is a view of one form of blank by means of which my invention may be carried out;

Fig. 5 is a side view of one form of completed upper embodying my invention;

Fig. 6 is a top view thereof, looking downward;

Fig. 7 is a view of the board shown in Fig. 1 with the blank shown in Fig. 4 applied thereto but before the blank has been stretched;

Fig. 8 is a similar view, showing the blank completely stretched; and

Fig. 9 is a perspective view of a shoe embodying my invention.

45 In all views like parts are designated by the same reference characters.

Referring to Figs. 1, 2 and 3 the board 1 is provided with a curved front 2. This curved front is substantially the same shape as the curve of the completed upper. Preferably this part of the board is shaped as shown. Associated with the curved edge of the board is a protuberance or spring 3.

This spring may be made of any suitable material, such as wood or metal. Preferably I attach it to the board by means of screws

4 so that it may be removed and a spring of different shape or size substituted. The spring is preferably made of the shape shown. Its front edge is removed a short distance from the curved edge of the board and is substantially parallel thereto. In cross section the spring is substantially triangular so that its highest part is substantially equi-distant from its front and rear edges.

Preferably the shoe upper is formed of leather as shown, or some other suitable material which may be stretched. The blank is formed with a part 6, which I denominate the "flat side" and a part 7, which I denominate the "full side". The full side is somewhat larger than the flat side for the purposes to be hereinafter referred to. The blank is creased along the line 8. This Fig. 4 shows at 10 the approximate position of the slit which is made in the blank after it has been stretched, as will be hereinafter described. It is to be understood that before stretching, the blank is unslitted. When so creased it is placed in position upon the board as shown in Fig. 7. When in this position the full side 7 of the blank will be on that side of the board which carries the spring 3. The blank will then be worked and stretched against the board so that the creasing line 8 will be made to assume the curve of the front 2 of the board. At the same time the full side 7 of the blank will be stretched over the spring 3 so that a fullness 9, see Fig. 8, will be produced.

When completed, the blank will be substantially as shown in Fig. 8, the side 6 having substantially the same superficial dimensions as the side 7. To permit this to be done the side 7 should be cut sufficiently large so that it will be the proper size and shape after being stretched to include the fullness. The blank is now slit at 10 at about the position of the dotted line in Fig. 4 and the solid line in Fig. 5. The two parts of the full side 7 adjacent to the slit will then be overlapped, see Figs. 5 and 6. In these views the complete shoe upper 11 is shown, with a button-hole flap 12, this button-hole flap being formed of the fullness 9 overlapping the cut edges after the slit 10 is made. That portion of the upper which is overlapped by the flap 12 forms the button flap and is of appreciable width for its entire length to allow for moving the button to adjust the shoe to fit feet of dif-

ferent sizes. The boot or shoe upper thus produced is attached to the sole and heel as shown in Fig. 9. This figure illustrates a shoe or boot with a one piece upper integral with the vamp and with the integral button flap. There is only one seam and that is at the back.

The invention may be modified in many ways. The location of the buttons may be anywhere desired. The upper need not be combined with an integral vamp. The shoe may not necessarily be a high shoe, as shown.

The process described is not claimed herein but is made the subject matter of a divisional application filed October 27, 1915 and numbered serially 58,117.

Having now described my invention, what I claim as new and desire to secure by Letters Patent, is:

1. A button shoe having a one piece upper, a flap carrying a row of buttons, said flap being of appreciable width for its entire length to allow for moving the buttons, a flap carrying a row of buttonholes, said flaps being integral with the upper and one overlapping the other, and a single seam in the upper, said seam being located at the back of the shoe.

Copies of this patent may be obtained for five cents each, by addressing the "Commissioner of Patents Washington, D. C."

2. A button shoe having a leather upper with a seam at the back, there being a slit at one side of the center of the front, and a flap carrying a row of buttons, said flap being of appreciable width for its entire length to allow for moving the buttons, there being a row of buttonholes at one side of the slit, the part having the buttonholes therein being integral with the upper and overlapping the flap.

3. A button shoe having a leather upper with a seam at the back, there being a slit at one side of the center of the front, and a flap carrying a row of buttons, said flap being of appreciable width for its entire length to allow for moving the buttons, there being a row of buttonholes at one side of the slit, the part having the buttonholes therein being integral with the upper and overlapping the flap, there being no seam in the center of the front of the upper.

This specification signed and witnessed this twenty seventh day of July, 1915.

JACOB GROSS.
